(57) **CLAIM**

The ornamental design for a water filtration pitcher, as shown and described.

DESCRIPTION

FIG. 1 is a top front perspective view of a pitcher of the present invention;

FIG. 2 is a bottom perspective view thereof;

FIG. 3 is a left side view thereof;

FIG. 4 is a right side view thereof;

FIG. 5 is a rear side view thereof;

FIG. 6 is a front side view thereof;

FIG. 7 it is top view thereof; and,

FIG. 8 is a bottom view thereof.

1 Claim, 7 Drawing Sheets
